The ornamental design for a wipes stand, as shown and described.

DESCRIPTION

FIG. 1 is a perspective view embodying the ornamental design of a wipes stand constituting my invention;

FIG. 2 is a front elevation view thereof;

FIG. 3 is a top plan view thereof;

FIG. 4 is a right side elevational view of the ornamental design for a rack, where the left side elevational view is a mirror image thereof;

FIG. 5 is a rear elevation view thereof; and,

FIG. 6 is a bottom plan view thereof.
